UNITED STATES PATENT OFFICE

TRUMAN W. DE TRAY, OF KENTON, ASSIGNOR OF ONE-HALF TO WILLIAM HARMAN, OF MALTA, OHIO.

WHIFFLETREE-HOOK.

SPECIFICATION forming part of Letters Patent No. 251,769, dated January 3, 1882.

Application filed September 9, 1881. (No model.)

To all whom it may concern:

Be it known that I, TRUMAN W. DE TRAY, of Kenton, in the county of Hardin and State Ohio, have invented new and useful Improvements in Single-Tree Hooks, of which the following is a specification.

The object of my invention is to construct the single or double tree hooks or the ferrules for neck-yokes in such a manner as to avoid the use of nails, screws, bolts, or like devices for attaching them to the single-tree or other like appliance, and also to permit of their being tightened should they become loose through the shrinkage of the wood; and to that end the invention consists chiefly in forming a series of spurs, commonly called "hawk's-bill spurs," upon the inner periphery of the sleeves of the single-tree hooks, and constructing them of wrought-iron, preferably, to fit over a shoulder formed on the single-tree or double-tree.

The invention further consists in providing the outer end of the sleeve with a peripheral flange fitting upon the outer end of the single-tree.

In the accompanying drawings, Figure 1 is an isometrical view; and Fig. 2, a longitudinal section on line $x x$ of Fig. 1, illustrating clearly my invention.

A represents the sleeve of the single-tree hook or the ring-sleeve of a neck-yoke, the former being provided with the hook a , the latter with an eye, to which the ring is attached. At the outer end of the sleeve of the single-tree hook is a peripheral inwardly-projecting flange, a' , adapted to fit over the outer end of the single or double tree, and upon the inner periphery of said sleeve are formed a series of spurs, b , adapted to fit over a shoulder, c , formed on the single-tree, as shown. When applied to a single-tree the hook-sleeve is slipped or forced over its ends in proper position or shrunk thereon, and the spurs are hammered down over the shoulder c , thus securing the hook firmly in position without having recourse

to the usual method of nailing or screwing said devices to the single-trees. The flange a' holds the sleeve against inward motion and the spurs b hold said sleeve against outward motion and against rotation. Should the sleeve become loosened in consequence of the shrinkage of the wood, said sleeve may be readily tightened by tightening or hammering down the spurs b .

Centrally of the double-tree, at that point where the ring-sleeve is applied, said tree or neck-yoke, as the case may be, is provided with two shoulders, c , on opposite sides of the sleeve, which in this case has, instead of a flange, a' , at one end, a second series of spurs, which prevent the end motion of said sleeve as well as its rotation upon the tree.

It will be observed that by means of this construction I provide a firm bearing for the sleeves, while by my improved construction and arrangement of said sleeves I provide a simple means of attachment without weakening the bearing for such sleeve by the usual driving of nails or screws, as well as means to tighten the sleeves should they become loosened by reason of shrinkage of the wood.

Having now described my invention, what I claim, and desire to secure by Letters Patent, is—

1. The combination, with the sleeve of a single-tree hook, of a series of spurs, b , upon one end and an inwardly-projecting flange, a' , upon the other end, as and for the purpose specified.

2. In combination with a single or double tree having the shoulders c , the sleeves A, having the spurs b and flanges a' , applied and operating as and for the purpose specified.

In witness that I claim the foregoing I have hereunto set my hand this 4th day of December, 1880.

TRUMAN W. DE TRAY.
